UNITED STATES PATENT OFFICE.

MAURICE T. STEVENS, OF HARVEY, ILLINOIS.

PIPE-MOLD.

SPECIFICATION forming part of Letters Patent No. 766,739, dated August 2, 1904.

Application filed May 20, 1902. Serial No. 108,192. (No model.)

To all whom it may concern:

Be it known that I, MAURICE T. STEVENS, a citizen of the United States, residing at Harvey, in the county of Cook and State of Illinois, have invented new and useful Improvements in Pipe-Molds, of which the following is a specification.

This invention relates to means for molding pipe from plastic material.

10 In view of the expense incident to the present mode of constructing drain, water, and other pipes and the disadvantages from a commercial standpoint arising from the usual burning or firing operations now generally 15 pursued a demand exists for a practical production of pipe in a cheap and more expeditious manner than has heretofore been practiced. Furthermore, it is necessary in the formation of pipe by the use of plastic material to render the same as nearly equally dense 20 throughout the length of the several pipe-sections as possible and at the same time maintain a uniformity of thickness throughout the body of the pipe.

25 The present means comprising coöperating elements have been devised for practically producing pipe-sections from cement or other plastic material which will closely adhere and become tenaciously homogeneous when dry 30 and practically of the same degree of hardness as the ordinary burned or fired pipe-sections now commonly in use. The improved means is arranged to concentrate pressure applied to opposite terminals of the pipe-sections molded in a longitudinal direction and to take advantage of a moist plastic filling and end layers or portions of relatively dry material similar to the filling to cause the moisture in the filling to be absorbed largely 35

40 by the relatively dry end portions of the molded section in order to relieve the intermediate filling of an excess of moisture, with a better result in the finished product. The improved means also comprises conveniently-

45 operated members or elements for forming a flange and flange-seat at opposite extremities of the molded pipe-section, the said members or elements being so constructed that they may be removed without injury to the corners or angles of the flange and flange-seat.

The improved means also contemplates the provision of simple and effective pressure-applying elements or members, as well as details of construction and arrangement of parts, which will expedite the formation of a pipe- 55 section.

In the drawings, Figure 1 is a longitudinal vertical section of the improved molding means and pressure devices, broken away in part and shown arranged in operative relation to a molding-pit. Fig. 2 is an enlarged transverse vertical section of a portion of one end of the improved means, particularly showing the devices for forming the flange at one end of the pipe-section. Fig. 3 is an enlarged 60 transverse vertical section of a portion of the opposite end of the molding element and particularly showing the means for forming the flange-seat at the opposite end of the pipe-section. Fig. 4 is a transverse vertical section 65 of the upper portion of the improved means embodying a modification in the construction and arrangement of parts. 70

Similar numerals of reference are employed 75 to indicate corresponding parts in the several views.

The numeral 1 designates an outer molding-casing, which is formed from suitable sheet-metal and cylindrical in contour. A cylindrical sheet-metal core 2 of tubular form is 80 adapted to be concentrically arranged in relation to the casing 1, said core being considerably less in diameter than the casing and slightly shorter than the latter. Co-operating with the casing 1 and core 2 is a 85 pressure-head 3 of less diameter than the casing, but adapted to snugly and movably fit in the latter, the said pressure-head having the lower end of a screw 4 swiveled thereon and provided with a hand-wheel or analogous 90 device 5. The screw movably extends through the center of a yoke 6, having one terminal formed with a hook 7 for engagement with an eye 8 on the upper end of a connecting-rod 9. To the opposite end of the yoke 6 the 95 upper end of a connecting-rod 10 is pivotally secured, the said rods 9 and 10 being equal in length and having their lower ends formed as inturned hook-terminals 11 to removably fit in openings 12 in the lower portion of a 100

tubular cylindrical pressure-head 13, which coöperates with the lower portion of the molding means.

The improved molding means also comprises in its organization annular molding-plugs 14 and 15, which are used in pairs in connection with opposite ends of the casing 1 and core 2 and are held in the space between the said casing and core. These molding-plugs at opposite ends of the casing 1 and core 2 are exact duplicates in construction, with the exception that the plug 14 which is used at the lower end of the molding means is greater in diameter than that used at the upper end of said means and the plug 15 at the lower end of the molding means is less in diameter than the similar device at the upper end of said means. Furthermore, the plugs 15 are of less width than the plugs 14, and the plug 15 at the upper end of the molding means is located around the outer face of the upper portion of the plug 14, whereas the lower plug 15 is applied to the inner face of its companion plug 14. It has been heretofore stated that the plugs 14 and 15 are exact duplicates in construction. They are, in fact, of such duplicate construction, except that the upper plug 14 has an outer inclined face 16, which bevels outwardly toward the casing 1, and the plug 15 a correspondingly inward beveled face 17 to bear against the face 16. At the bottom of the molding means the outer plug 14 has a lower inwardly inclined face 18 and the plug 15 has an outer correspondingly upwardly and outwardly inclined face 19. It will be observed that the difference in construction is simply one of reversal of the inclined faces, and by the provision of such faces breaking of the corners or angles of the flange and flange-seat at opposite extremities of the pipe-section will be prevented, as the plugs 15 can be first withdrawn, and thereby reduce the resistance to withdrawal of the plugs 14. The pressure-head 3 contacts directly with the adjacent end of the tubular core 2 and the plugs 14 and 15; but the lower tubular pressure-head 3 contacts at one end with an interposed annular pressure-plate 20, which is made in two sections and closely fits in between the casing 1 and core 2. The purpose of making the pressure-plate 20 in two sections is for convenience in removing the same and to avoid sticking of the said plate which might occur if it were made of one piece.

In preparing the mold for use the plugs 14 and 15 are inserted between the casing 1 and core 2, at the lower terminals of the latter, the sectional pressure-plate being then applied to the outer ends of the plugs and the one end of the tubular pressure-head 13 brought to bear against the said pressure-plate. It will be understood that when the pressure-head 13 is brought to bear against the pressure-plate 20 the rods 9 and 10 will have their lower

terminals connected to said pressure-head; but the opposite or upper end of the molding means will be open, or, in other words, the pressure-head 3 will be thrown back or elevated, so as to leave the space between the casing 1 and core 2 freely accessible at the upper end of the molding device. A quantity of relatively dry plastic material, such as cement, is then introduced into the space and is packed closely against the plugs 14 and 15, engaging the lower extremities of the casing 1 and core 2, as clearly indicated by heavy section-lines in Fig. 1. After a suitable amount of this relatively dry plastic material is thus introduced an intermediate moist quantity of similar material is poured or pushed into the space between the casing and the core and closely packed, and finally an upper quantity or layer of relatively dry plastic material is disposed in the space between the casing and the core on top of the moist intermediate filling of such material. The upper plugs 14 and 15 are then pushed into place, the pressure-head brought down over the plugs and in contact with the upper end of the core 2, and the rod 9 is connected to the hook 7 of the yoke 6. The mold or molding means will then be in condition for applying pressure to the plastic filling within the space between the casing 1 and core 2, and to render the operation effective the lower end of the mold, including the lower pressure-head 13 and the lower extremities of the rods 9 and 10, is disposed in a suitably-formed mouth 21 at the upper extremity of a pit 22. The operator then rotates the hand-wheel 5 in a proper direction to cause the pressure-head 3 to move downwardly and draw the pressure-head 13 upwardly. The pressure-head 3 being in contact with the upper end of the core 2 will push the latter longitudinally through the plastic mass in the space between the casing 1 and core 2, and by a continual exertion of pressure on the material being molded in opposite longitudinal directions the moisture in the intermediate filling will be absorbed by the relatively dry terminal layers or portions of the similar material, and thereby equalize the disposition of the moisture throughout the entire pipe-section and relieve the intermediate portion of the pipe-section of an excess of moisture. This equalization of the disposition of moisture longitudinally of the molded pipe-section will cause the latter to dry out more evenly and also render the molded mass substantially equal in density throughout its length and more perfectly homogeneous. After the material has been sufficiently compressed the rods 9 and 10 are disconnected from the pressure-head 13, the pressure-head 3 and parts connected thereto elevated and turned to one side, and the core 2 pushed down into the pit. The plugs 14 and 15 at opposite ends are disconnected or removed from the molded mass, and the pipe-section,

with the outer casing around the same, is then ready for shipment or storage, it being preferred to maintain the intimate relation of the casing 1 and the molded section until it is 5 desired to use the latter in order to prevent injury to the same.

The modified formation of the device shown by Fig. 4 embodies an upper pressure-head 23, having a depending rim 24 to contact with 10 an annular pressure-plate 25, which is introduced in the space between the casing 1 and the core 2. This form of upper pressure-head 23 operates similarly to the lower pressure-head, (shown by Fig. 1,) and in using this arrangement of parts the core 2 is not pushed longitudinally through the molded section, but is afterward removed by any suitable means. The remaining parts of the mold, as 15 shown by Fig. 4, are similar to those heretofore described.

From the foregoing it will be seen that a simple and effective mold or molding means for producing pipe-sections from plastic or other analogous material is provided, and 20 while the preferred structure of the several parts has been disclosed it will be understood that changes in the form, proportions, dimensions, and minor details may be resorted to without departing from the spirit of the invention.

Having thus fully described the invention, what is claimed as new is—

1. In a molding means, an outer casing, a core spaced apart therefrom to permit a molding material to be introduced between the casing and core, a pressure-head fitting within the upper end of the casing, a pressure-head situated within the lower end of the casing, a plug interposed between the molding material and upper pressure-head and adapted to fit around the core and provided with an outer beveled face, a plug of less width adapted to be interposed between said beveled face and the casing, a plug interposed between the molding material and the lower pressure-head and adapted to engage the inner surface of the casing and provided with an inner beveled face, a plug of less width adapted to be interposed between said last-mentioned beveled face and the core, and means for connecting the pressure-heads together and causing them to approach each other.

2. In a molding means, an outer casing, a core spaced apart therefrom to permit a molding material to be introduced between the casing and core, an upper pressure-head, a lower pressure-head, rods connected to the lower pressure-head, a yoke pivotally secured to one of said rods and adapted to removably engage the other, and a screw swiveled upon the upper pressure-head and movably extending through the yoke.

3. In a molding means, an outer casing, a core spaced apart therefrom to permit a molding material to be introduced between the cas-

ing and core, a pressure-head fitting within the upper end of the casing, a pressure-head situated within the lower end of the casing, a plug interposed between the molding material and upper pressure-head and adapted to fit 70 around the core and provided with an outer beveled face, a plug of less width adapted to be interposed between said beveled face and the casing, a plug interposed between the molding material and the lower pressure-head 75 and adapted to engage the inner surface of the casing and provided with an inner beveled face, a plug of less width adapted to be interposed between said last-mentioned beveled face and the core, a plate interposed between 80 the plugs and lower pressure-head, and means for connecting the pressure-heads together and causing them to approach each other.

4. In a molding means, an outer casing, a concentric core spaced apart therefrom to permit a molding material to be introduced between the casing and core, a pressure-head fitting within the upper end of the casing, a pressure-head situated within the lower end of the casing, sectional plugs introduced between the pressure-heads and molding material, and means for connecting the pressure-heads together and causing them to approach each other to exert a longitudinal pressure in opposite directions on the molding material. 85

5. In a molding means, an outer casing, a concentric core spaced apart therefrom to permit a molding material to be introduced between the casing and core, a pressure-head fitting within the upper end of the casing, a pressure-head situated within the lower end of the casing, plugs introduced between the pressure-heads and molding material, a pressure-plate interposed between one of the plugs and pressure-heads, and means for connecting 100 the pressure-heads together and causing them to approach each other to exert a longitudinal pressure in opposite directions on a molding material. 105

6. In a molding means, an outer casing, a concentric core spaced apart therefrom to permit a molding material to be introduced between the casing and core, a pressure-head fitting within the upper end of the casing, a pressure-head situated in the lower end of the casing, plugs introduced between the pressure-heads and molding material, a sectional pressure-plate interposed between one of the plugs and pressure-heads, and means for connecting the pressure-heads together and causing them to approach each other to exert a longitudinal pressure in opposite directions on a molding material. 110 115 120

In testimony whereof I affix my signature in presence of two witnesses.
